UNITED STATES PATENT OFFICE.

PIERRE I. CHANDEYSSON, OF ST. LOUIS, MISSOURI.

RHEOSTAT.

Application filed April 18, 1922. Serial No. 554,469.

To all whom it may concern:

Be it known that PIERRE I. CHANDEYSSON, a citizen of the United States of America, residing at St. Louis, in the county of St.

5 Louis and State of Missouri, has invented certain new and useful Improvements in Rheostats, of which the following is a specification.

This invention relates to improvements 10 in rheostats and provides means of introducing or cutting out simultaneously, resistance into separate or distinct circuits.

Certain types of generators, notably low voltage machines, are provided with two 15 commutators for various reasons. These generators are operated sometimes with the armature circuits in parallel, sometimes as three wire machines, and sometimes with the two commutators in series.

20 When so used, my rheostat permits of the excitation of such generator so that each side or each commutator of the armature furnishes exactly one half of the exciting current, and it further gives the advantage that 25 when the generator is so connected, it can be operated either as a three wire machine or as a two wire machine, with the outside leads either in parallel or in series without making any change whatsoever in the shunt 30 connections.

As constructed for commercial purposes preferably in accordance with the following specification,

35 My rheostat, briefly will consist of two resistances, coiled generally in one piece, each resistance embodying a plurality of loops or turns at suitable intervals, which loops are fastened to a series of posts insulated from their support, the face of the post extending 40 above the face of the support, constituting a flat surface from which a rubbing contact of suitable material can travel and conduct the current from these surfaces to a suitably disposed conductor, on which the other part of the rubbing contact brush rests.

45 Two such sets of resistance binding posts with their projecting flat contact surfaces are so mounted that conducting brushes at the opposite extremity of a lever pivoted 50 centrally between them, can be moved thru an arc of about 180°, and during its travel, short-circuit simultaneously on both sides the binding posts to which the resistance is attached to the metallic surface to which the 55 current is admitted or from which the current is led away from the apparatus.

In the accompanying drawings which illustrate a preferred embodiment of my invention,

Figure 1 is a plan view of the rheostat; 60

Figure 2 is a vertical sectional view of the rheostat with the brush carrying lever moved to a position about 90° spaced from that shown in Figure 1; and

Figure 3 is a diagrammatic view of the resistance, illustrating the coils and their connections with the contacts. 65

Referring more particularly to the drawings by numerals of reference, I provide a rheostat casing 2 of metal, said casing being 70 of a dome-shape to provide therebeneath a recessed portion 4 within which are housed and protected, the coils of the rheostat to be later described, the flanges of which casing are provided with a suitable number of 75 spaced ears 6 by which the device may be attached to an instrument-board or wherever its service is required.

The crown or upper face of the dome-shaped casing is provided upon each side of 80 a medium line with a semicircular series of openings 8, thru which pass the shanks 9 of a series of contacts 10, secured in position within the openings thru nuts 12, said contacts being insulated from the metal casing 85 by sheets 14 of suitable insulating material such as mica or compressed fibre board. The openings 8 are of course larger in diameter than the diameter of the shanks 9 of the contacts so that there is no electrical connection 90 between them and the casing.

A resistance 15 which is preferably formed from a single piece of suitable resistance wire to avoid uncertain resistance of joints, embodies a series of coils 16, each of which is 95 formed of a suitable number of convolutions, said coils being provided with inter-connecting portions 18 of U-shape which straddle the extension of the contact shank, and upon the threaded end 19 of which is applied a nut 20 which clamps or binds the portions 18 securely against the under face of the nut 12 and in good electrical contact therewith.

The current is led into the rheostat thru a connector 22 having a socket 24 into which is inserted the bared end of the conductor, which latter is bound by screws 25, said connector being secured upon the upper face of the casing by a screw 26 also suitably insulated. Said connector is further secured 105 in position thru a bolt 28 which passes thru the inner end thereof and thru the end one 110

of the series of openings 8 in the casing and from which it is insulated by the same plate of insulating material which serves for the several contacts.

- 5 The terminal of the last coil is bound to the shank of the contact which is designated at 10^a, the interconnecting portions between the several coils being connected as has been stated to the shanks of the several contacts 10 until finally the terminal of the first coil is bound between the nuts 30 and 31 of the bolt 28 which secures the connector 22 on the casing and also serves as the conductor.

Concentric with each series of contact 10 15 and arranged inwardly thereof is an arenate electrical contact rubbing plate or strip 34 one end of which terminates adjacent the last of the contacts and is secured upon the crown or upper face of the casing thru bolts 20 36 passing thru openings 38 arranged in said casing, said bolts and said contact strip being insulated by the insulating sheets 14. The strip 34 is preferably formed integral with an outlet connector 40 similar to the 25 inlet connector 22.

The switch member which brings into operation the variable resistance in the circuit in which the rheostat is included comprises a lever 42 having a pair of diametrically opposite arms 44 provided adjacent their ends and upon the lower face of each with a socket 46 within which is disposed a bridge piece 48 of suitable material, for instance, spring copper leaves, said bridge 30 35 piece being suitably secured within the socket by such means as an insulated bolt and nut arrangement 50 and insulated from the supporting arm by an insulation sheet 52.

The lever 42 is mounted for oscillation 40 upon a post 54 journalled centrally of the upper face of the casing in an enlargement thereof and is urged downwardly to maintain the bridge piece 48 in contact with the contact members 10 and 34 by a tension 45 spring 56 coiled around the lower extension of the post 54 and seated intermediate the lower face of the enlargement and a cross pin 59. The lever is provided with a knot 60 for operating it.

50 It is obvious that the current entering by

the terminal connectors 22 passes thru the coils, across the bridge members of the switch lever, back thru the rubbing contact strips and out at the terminals 40.

It is evident from the description that my 55 rheostat can be utilized for other purposes than to regulate the current in two parts of the field circuit of a motor or a generator; for instance, the two independent resistances may be connected as one resistance either in 60 parallel or in series, or they can be used separately for controlling current simultaneously into two different circuits; for instance, into two electroplating tanks or on only one of them.

Having thus described my invention, what I claim is:—

1. A rheostat comprising a substantially dome shaped casing provided with a plurality of sets of spaced contacts, an arcuate 70 contact plate arranged adjacent each set of spaced contacts, a resistance element supported in the dome of said casing and connected with certain of the contacts, said resistance element comprising a series of spiral 75 coils with interconnecting loops, said loops adapted to straddle the aforesaid contacts, a rotatable element journaled on the casing, and U-shaped conductors carried thereby and adapted to bridge the spaces between 80 the plates and the spaced contacts.

2. A rheostat comprising a substantially dome shaped casing provided with a plurality of sets of spaced contacts, an arcuate contact plate arranged adjacent each set of spaced contacts, a resistance element supported in the dome of said casing and connected with certain of the contacts, said resistance element comprising a series of spiral 85 coils with interconnecting loops, said loops 90 adapted to straddle the aforesaid contacts, a rotatable element journaled in the casing, and having arms extending laterally therefrom, said arms being provided with concaved sockets on their lower sides and U-shaped conductors carried in said sockets 95 and adapted to bridge the spaces between the plates and the spaced contacts.

In testimony whereof I affix my signature.
PIERRE I. CHANDEYSSON.
